Attorney

UNITED STATES PATENT OFFICE.

ANDRZEJ KUBECZKO, OF CHICAGO, ILLINOIS.

SHIP-PROTECTOR.

1,280,246.

Specification of Letters Patent.

Patented Oct. 1, 1918.

Application filed November 30, 1917, Serial No. 294,625.

To all whom it may concern:

Be it known that I, ANDRZEJ KUBECZKO, a citizen of Russia, residing at Chicago, in the county of Cook and State of Illinois, have invented certain new and useful Improvements in Ship-Protectors, of which the following is a specification.

The primary object of the invention is the provision of a resilient means carried by the hull of a vessel for warding off and rendering ineffectual any missiles approaching the vessel at a point adjacent the water line, the arrangement being such as to offer only slight resistance to the travel of the vessel through the water.

A further object of the device is the provision of a buffer means carried at the opposite sides of a ship's hull for cushioning and absorbing the shocks of oncoming missiles.

In the drawing forming a part of this application and in which like designating characters refer to corresponding parts throughout the several views,

Figure 1 is a side elevation of a ship provided with the device.

Fig. 2 is a horizontal sectional view through the hull showing a central portion of the device upon an enlarged scale.

Fig. 3 is an enlarged vertical transverse sectional view thereof.

Fig. 4 is an enlarged horizontal detail view showing the hinge arrangement for the members, and

Fig. 5 is an enlarged plan view adjacent one of the hinge members.

Referring more in detail to the drawing, my device broadly consists of a plurality of resilient armor plates 10 adapted to be attached to the opposite sides of a hull such as 11 of a ship 12, the latter having a deck 13 arranged with a cabin 14, funnels 15, and wireless apparatus 16, the usual rudder 17 and propeller 18 being arranged for the ship.

Outwardly projecting brackets 19 are carried by the hull 11 having parallel supporting arms 20 arranged with longitudinal slots 21 closed at the outer free ends of the said arms. The plates 10 are substantially rectangular in form and arcuate in longitudinal section, the same being formed of resili-

ent material such as thin sheet metal and being hollow with a receiving chamber 22 within each plate 10.

A filling is arranged within the chamber 22 consisting of feathers or sponges 23 and resilient material such as rubber 24, the latter being arranged adjacent the outer face of the plate. A pintle 25 is adapted for hinging together the adjacent plates 10 and extends through the slots 21 of the arms 20 with the headed ends 26 of the pintle positioned outwardly of the adjacent arm. It will be understood that the plates 10 are not only connected together by means of the bolts 25, but the plates are also horizontally shiftably mounted upon the arms 21 carried by the hull 11, the inward movement of the plates 10 toward the hull being limited by the inner ends 27 of the slots 21 being contacted by the pintles 25.

A plurality of springs 28 are tensioned between blocks 29 upon the hull 11 and similar blocks 30 carried by the plates 10, whereby the said plates are normally positioned at the extremity of their movements outwardly of the hull. The plates 10 are arranged in this manner adjacent the water line of the hull 11 and any oncoming missile will hit the outer face of the plates 10 adjacent the rubber layer 24 which will cushion the blow, the shock being further absorbed by the layer of feathers 23. The force of the blow upon the plates 10 will be also exerted upon the springs 28 and the plates 10 will be forced inwardly toward the hull by the force of the missiles but by reason of the several cushioning elements provided by the device, the missile will be gently stopped and prevented from striking the hull 11. The plates 10 will offer very little resistance to movement of the ship 12 through the water and the plates will also serve as a buffer when approaching a dock or another ship. The plates 10 are preferably extended to entirely surround the hull 11 being connected together at the stern 31 and bow 32.

What I claim as new is:—

1. The combination with the hull of a ship, of brackets carried by the sides thereof having horizontal outwardly projecting upper and lower arms provided with vertically aligned longitudinal slots, a plurality of

resilient armor plates, vertical hinging pintles connecting said plates and having their ends slidably arranged in said slots of the bracket arms, and cushioning springs between the hull and the armor plates.

2. The combination with the hull of a ship, of outwardly projecting brackets secured to the sides of the hull adjacent the water line and having parallel horizontal upper and lower arms provided with vertically aligned longitudinal slots of substantially equal length, a plurality of hollow arcuate plates, vertical pintles hingedly connecting said plates and having their ends slid-

ably arranged in said slots of the bracket arms, a resilient filling within each of said plates, and resilient means between the hollow plates and the hull.

3. A ship protecting plate comprising a hollow rectangular member arcuate in longitudinal section and formed of resilient material, a layer of hard rubber within the member adjacent the convex side thereof, and a layer of feathers within the member adjacent the concaved side thereof and contacting the rubber layer.

In testimony whereof I affix my signature.

ANDRZEJ KUBECZKO.
